UNITED STATES PATENT OFFICE.

ELLIS L. ROWE, OF TROY, NEW YORK, ASSIGNOR TO THE RENSSELAER MANUFACTURING COMPANY, OF SAME PLACE.

VALVE-INDICATOR.

SPECIFICATION forming part of Letters Patent No. 606,584, dated June 28, 1898.

Application filed January 27, 1898. Serial No. 668,221. (No model.)

To all whom it may concern:

Be it known that I, ELLIS L. ROWE, of Troy, in the county of Rensselaer and State of New York, have invented certain new and useful 5 Improvements in Valve-Indicators; and I hereby declare that the following is a full, clear, and exact description thereof, reference being had to the accompanying drawings, which form part of this specification.

10 This invention is an improvement in valve-indicators designed to disclose at a glance whether the valve to which the indicator is attached is opened or closed; and the objects of the invention are to provide an indicator 15 attachment which may be readily applied to many kinds of valves and in which one sign is fixed and the other movable and of such relative form that it would be impossible for malicious persons to interchange them.

20 The invention therefore consists in the novel construction and combination of parts hereinafter described and claimed, and the accompanying drawings illustrate the same as applied to ordinary forms of valves.

25 Figure 1 is a perspective view of a straightway valve having a screw stuffing-box with my improved indicator attached thereto. Fig. 2 is an enlarged vertical section through the indicator. Fig. 3 is a perspective view 30 of the various parts of the indicator mechanism detached. Fig. 4 is a perspective view of a valve having a bolted stuffing-box, showing the indicator slightly modified; so as to be more readily applicable to such valve. Fig. 35 5 is a perspective view of part of the indicating mechanism shown in Fig. 4. Fig. 6 is a detail showing a slight modification.

40 A designates an ordinary straightway valve having a spindle or stem B, which ordinarily has no longitudinal movement, but is adapted when rotated to raise and lower the valve-gates by various well-known means, (not shown,) description thereof being unnecessary here.

45 As shown in the drawings, the spindle is operated by the hand-wheel b; but of course it may be rotated by other means.

The indicating device consists of a stationary shield or blind D, which is rigidly attached to a support adapted to be secured to

the valve-casing beside the stuffing-box, and parallel with and behind this blind, but projecting above the same, is a standard E, also rigidly connected to the support, and on the outer face of said standard, at a point above 55 the blind, is an indicating-legend, as "Shut." This legend may be cast on a metal plate e and secured to the standard by screws, as indicated in Fig. 3 of the drawings. The support for the blind and standard will necessarily be varied to suit the different styles of valve-casings to which the indicator is attached.

As shown in Figs. 1 and 2, where the casing has a screw stuffing-box, the support consists 60 of an annulus F, which is preferably provided on its interior with inwardly-projecting lugs f, that are adapted to center the standard around the base of the stuffing-box, as indicated in Fig. 1, and said annulus is firmly 65 secured in place by means of a tap-bolt F'. As shown in Figs. 4 and 5 the support is adapted to a casing having a bolted stuffing-box, and, in this instance, consists of a flat plate G, adapted to fit between the upper and lower flanges of 70 the stuffing-box, and provided with holes g for the passage of the box-adjusting bolts g², and is retained in place by means of auxiliary nuts g³ on said bolts, as indicated in Fig. 4. The construction of the support is not of the 75 essence of the invention and must necessarily vary with the construction of the valve-casing, and it might be possible in some valves to make the standard and blind integral with the casing. It is essential, however, that the 80 parallel blind and standard be used substantially as indicated in the drawings.

The other legend, "Open," is on the outer face of a movable bracket H, which preferably has a loop H' behind the legend and adapted 90 to loosely fit over the standard E, so that this portion of the bracket may slide up and down on said standard. The bracket has an inwardly-extending arm H², by which it is connected to a ring H³, which is interiorly threaded 95 to engage a threaded portion I on the stem. This threaded part I may be simply a threaded sleeve which can be secured to the spindle B above the stuffing-box by means of set-screws i, thus enabling the indicating device to be 100.

easily applied to valves already made or in use.

The legend "Open" may be formed on a plate *h*, detachably secured to the bracket *II* by screws *h'*, as indicated in Fig. 3.

The parts of the indicator are so attached to the valve that when the valve is shut the loop *II'* of the bracket will be lowered beneath the top of and behind blind *D*, so that the legend "Open" is totally obscured by the blind, while the legend "Shut" is disclosed in full view. (See Fig. 1.)

When the valve is open, the bracket *II* is raised above the blind *D* until the loop *II'* 15 totally obscures the legend "Shut," the legend "Open" only being then visible. (See Fig. 4.) This reciprocating movement of the bracket *II* is caused by the engagement of ring *II³* with the threaded portion *I* on the valve-stem 20 and because the bracket is prevented from rotating by the engagement of its loop *II'* with the standard *E*.

The indicator can be readily attached to nearly all regular valves now in use by employing the threaded sleeve *I*, which is slipped over the regular spindle and fastened by a screw *i* in a countersunk hole in the sleeve. However, when new valves are made the spindle itself might be constructed with 30 an integral threaded portion *I*.

On regular small valves where the angular support *F* is used the indicator can be turned to any point desired around the valve and secured by means of a set-screw, as shown.

35 On larger-sized valves having bolted stuffing-boxes the indicator can be adjusted to any position allowed by the bolts used in the construction of the stuffing-box. The "Open" sign is preferably on the part that travels.

40 The "Shut" sign is preferably on the stationary part. In some instances, however, these legends might be constructed to read oppositely, but the position of the "Open" and "Shut" signs on the indicator cannot be 45 changed by malicious persons exchanging the sign-plates one for the other and thereby indicating that the valve is in a position different from what it actually is, as the sign-plates are not interchangeable, being of different 50 shapes, and one cannot be substituted in place of the other without detection.

If the valve is placed with the wheel down, as is sometimes necessary, each sign can be 55 removed, reversed, and replaced so as to read correctly in the inverted position of the valve.

From the foregoing description it will be seen that I have a very simple but efficient indicator attachment, readily applicable to a great variety of valves, and although I have 60 described the same as applied to a valve whose spindles are not longitudinally movable it is obvious that the device could be as readily applied to a device with a movable spindle, as in that case the part *I* and ring *II³* would cause the bracket *II* to move longitudinally with the valve-stem; but in such 65 cases the threaded portion *I* might be re-

placed by collars above and below the ring *II³*, as indicated in Fig. 6.

Having thus described my invention, what I therefore claim as new, and desire to secure by Letters Patent thereon, is—

1. In an indicator for valves, the combination of a stationary blind, and the stationary legend behind and above the blind; with a bracket carrying a movable legend and operated by and from the valve-spindle so as to raise said movable legend above the blind, thereby obscuring the stationary legend, or lower the movable legend behind the blind, thereby uncovering the stationary legend, substantially as described.

2. In an indicator for valves, the combination of the standard and blind, said standard projecting above the blind and carrying a legend on its face above the blind; with a movable bracket operated from the valve-spindle adapted to slide upon the standard and carrying a legend, said bracket obscuring the stationary legend when raised, and said blind obscuring the movable legend when the bracket is lowered, substantially as described.

3. In an indicator for valves, the combination of the parallel standard and blind fixedly attached to the casing, said standard projecting above the blind and carrying a legend on its outer face, with a movable bracket adapted to slide upon the standard and carrying a legend on its outer face; and means for operating said bracket from the valve-spindle, said bracket obscuring the stationary legend when raised, and said blind obscuring the movable legend when the bracket is lowered, substantially as described.

4. In a valve-indicator, the combination of a blind and a standard parallel with and behind the blind, having a legend on its front face above the blind; with a movable legend adapted to be reciprocated between the standard and blind and to obscure the fixed legend when raised, and to be itself obscured by the blind when lowered, and means for raising and lowering said movable legend operated from the valve-spindle, substantially as described.

5. In a valve-indicator, the combination of a support adapted to be secured to the valve-casing, a blind attached to one side of said support, and a standard attached to said support parallel with and behind the blind, said standard having a fixed legend on its front face above the blind, with a movable legend operated from the valve-spindle adapted to be reciprocated between the standard and blind and to obscure the fixed legend when raised, and to be itself obscured by the blind when lowered, substantially as and for the purpose described.

6. In an indicator for valves, the combination of the parallel blind and standard rigidly connected to a support detachably secured to the casing, said standard having a legend on its outer face; with a vertically-movable bracket operated by and from the

valve-spindle and carrying a legend on its outer face adapted to obscure the stationary legend when the bracket is raised, and to be itself obscured when the bracket is lowered, substantially as and for the purpose described.

7. The combination with a valve, of an indicator consisting of a blind and a standard parallel with and behind the blind, said standard having a fixed legend on its outer face above the blind; with a bracket having a loop adapted to embrace the standard and a legend on the outer face of said loop, said bracket having a ring loosely engaging the valve-spindle, whereby the bracket is reciprocated when the valve-stem is rotated, and the legend on the outer face of the bracket obscured by the legend on the standard when the bracket is raised, or itself obscured by the blind when the bracket is lowered, substantially as described.

8. The combination with the valve, of a support detachably connected thereto, a blind outside of and connected to said support, and the standard parallel with and behind the blind, also connected to said support, said standard having a fixed legend on its outer face above the blind; with a bracket having a loop carrying a legend on its outer face and adapted to embrace the standard and said bracket also having a threaded annulus engaging a threaded portion on the valve-spindle, whereby the bracket is reciprocated when the valve-stem is rotated, so as to cause the legend on the outer face of the bracket to obscure the legend on the standard when the bracket is raised, or to be obscured by the blind when the bracket is low-

ered, substantially as and for the purpose described.

9. The combination with the spindle and casing, of a valve; of an indicator, consisting of a blind and a standard parallel with the blind, said standard bearing a legend on its outer face above the blind, a threaded sleeve secured to the spindle above the stuffing-box, and a bracket having a threaded ring engaging said sleeve, and a loop fitting over said standard, said loop having a legend on its outer face obscured by the blind when the bracket is lowered, and obscuring the legend on the standard when the bracket is raised, substantially as described.

10. The combination with the spindle and casing of a valve, of a valve-indicator, consisting of a support detachably connected to the casing beside the stuffing-box thereof, a blind and a standard parallel with the blind, both secured to the said support, said standard bearing a legend on its outer face above the blind, a threaded sleeve made fast to the spindle above the stuffing-box, and a bracket having a threaded ring engaging said sleeve and a loop embracing said standard, and having a legend on its outer face obscured by the blind when the bracket is lowered, and obscuring the legend on the standard when the bracket is raised, all substantially as and for the purpose described.

In testimony that I claim the foregoing as my own I affix my signature in presence of two witnesses.
